(57) **CLAIM**

The ornamental design for an automatic feeding device for animals, as shown and described.

DESCRIPTION

FIG. 1 is a front elevational view of an automatic feeding device for animals showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a top, front and right side perspective view thereof;
FIG. 8 is a top, rear and right side perspective view thereof;
FIG. 9 is a top, front and right side perspective view showing the automatic feeding device for animals in a first position of use showing unclaimed environmental subject matter;
FIG. 10 is a top, front and right side perspective view showing the automatic feeding device for animals in a second position of use showing unclaimed environmental subject matter; the bottom of the device is contained within the unclaimed environmental subject matter; and,
FIG. 11 is an enlarged detail view of area 11 circumscribed within FIG. 7.

The oblique shading lines in the drawings are included to denote the transparent or translucent quality of the surface planes of the automatic feeding device for animals. The evenly spaced broken lines and unshaded areas throughout the drawings depict portions of the automatic feeding device for animals which form no part of the claimed design. The dot dash dot broken lines in the drawings denote the boundaries of the detail areas and form no part of the claimed design. The evenly spaced broken lines in FIG. 9 and FIG. 10 depict environmental subject matter that forms no part of the claimed design.

1 Claim, 11 Drawing Sheets
